(57) **CLAIM**

The ornamental design for air quality monitor, as shown and described.

DESCRIPTION

FIG. 1 is a front perspective view of an air quality monitor in accordance with the new design.

FIG. 2 is rear perspective view thereof.

FIG. 3 is a front elevation view thereof.

FIG. 4 is a back elevation view thereof.

FIG. 5 is a side elevation view thereof.

FIG. 6 is an alternate side elevation view thereof, showing the side opposing that shown in FIG. 5.

FIG. 7 is a top elevation view thereof.

FIG. 8 is a bottom elevation view thereof.

FIG. 9 is an alternative front perspective view of an air quality monitor.

FIG. 10 is an alternative front elevation view thereof; and, FIG. 11 is an alternate top elevation view thereof.

The broken lines showing text in FIGS. 9, 10, and 11 form no part of the claimed design.

1 Claim, 6 Drawing Sheets
